APPARATUS FOR CLASSIFYING OR GRADING CRUSHED ORE AND THE LIKE.

1,040,804.

Specification of Letters Patent.

Patented Oct. 8, 1912.

Application filed September 30, 1911. Serial No. 652,208.

To all whom it may concern:

Be it known that I, GEORGE HARDY STANLEY, a British subject, residing at the South African School of Mines and Technology,

- 5 Johannesburg, Transvaal, have invented new and useful Improvements in Apparatus for Classifying or Grading Crushed Ore and the Like, of which the following is a specification.
- 10 Crushed ore and like pulverulent material has hitherto commonly been graded both by hydraulic classification and by screening. Separation effected solely by hydraulic methods is always imperfect; largely owing 15 to the practical difficulty of obtaining a precisely uniform stream of liquid in which to effect the settlement of the larger and (or) heavier particles. While therefore it is at present possible to obtain from a hydraulic classifier an underflow containing practically no material of less size than that desired, this can only be done upon so increasing 20 the velocity of the current as to carry an undue proportion of the larger material 25 away with the overflow. On the other hand screening possesses the advantage of enabling well defined products to be obtained, but has not hitherto been largely employed owing to the relatively low output and constant tendency to choke. In ore screening 30 operations hitherto known, the material has been fed onto the screen from above and has passed through the same by gravity, assisted frequently by water sprays, vibration 35 or brushing of the screen, and the like. In all such cases not only, on the one hand, is the gravitational movement of the finer material through the screen hindered and rendered sluggish by the clinging tendency of 40 said material, but on the other hand the oversize is necessarily retained on the surface of the screen for a relatively long period, *i. e.*, while traveling from the point at which it is fed to the point of discharge 45 from the screen, during the whole of which period it blinds a comparatively large proportion of the screen apertures.

The present invention consists in a combined hydraulic and screening apparatus, 50 which affords the large output of the hydraulic system with the precision obtainable by the use of screens.

The invention also consists in a hydraulic classifier provided with mechanical and positive means of high capacity for separating 55

from the overflow the oversize material which would otherwise be carried off with it and returning such material to the underflow.

According to the method of the present invention, the granular material in admixture with liquid is subjected to hydraulic classification by flowing it in any appropriate manner to cause the settlement of the heavier and (or) larger material. The rate 60 of settlement in this step is so adjusted that none of the lighter and (or) smaller material which it is desired to carry off with the overflow will settle at this stage with the heavier and (or) larger material; or 65 at least so that the proportion of such lighter and (or) smaller material which so settles is substantially less than in the present methods. As a consequence, a relatively 70 large proportion of heavier and (or) larger 75 material will be carried on without settlement. The liquid carrying the remaining material is now passed through a screen of the proper mesh to arrest oversize material. The screen is so positioned in relation to the 80 overflowing stream that solid particles of the pulp are or tend to be carried through it solely by the flow of the liquid in contradistinction to the present gravitational method, and so also that material rejected 85 by the screen tends to fall directly therefrom by gravity. Thus, the screen may be set vertically or inclined toward the oncoming pulp. The screen is also appropriately reciprocated or shaken, preferably by being 90 bumped longitudinally. In the case of a vertical screen, it is reciprocated vertically and bumped or jerked on the down stroke and similarly in the case of an inclined screen. The surface of the screen may be 95 flat, curved, corrugated or of other form.

The invention may be carried out by providing the overflow discharge outlet of any appropriate type of hydraulic classifier with a reciprocating screen fitted in the manner 100 described and through which the overflow is caused to pass.

In the accompanying drawings Figure I is a vertical section of an upward current hydraulic classifier arranged according to 105 this invention, and Fig. II is a vertical section of an ordinary cone classifier modified in accordance with the invention.

Referring to Fig. I, the casing *a* is divided into two compartments *b* and *c* by a 110

partition *d*. *e* is a launder for the supply of pulp. The bottom of the casing is curved or sloped as shown and the bottom of the partition is correspondingly shaped to form therewith a constricted passage *f* through which pulp will pass rapidly and in a regular stream from compartment *b* to compartment *c*. In order to obtain the best results compartment *c* should increase considerably 5 in area toward the top. In the course of passage *f* there is formed a slot *g* or other opening leading to a collecting chamber *h* or a pipe for the larger or heavier material, whence said material is discharged by means 10 of a siphon or other known device. *k* is a pipe for supplying hydraulic water in the known manner. The screen *l* forms part of one side of the compartment *c* and may conveniently be set substantially vertically as 15 shown. It is arranged to slide vertically in a housing *m* and is reciprocated by such means as the lifting tappet *n* and the spring *o* tending to force it downward. The reciprocations should be rapid, but need be of 20 but small amplitude. The effect of tappet *n* and spring *o* is to cause the screen to be bumped at the end of each small downward movement. All particles which are too 25 large to pass the screen but which are held against the same by the flow of the liquid are thereby detached from the screen and projected downward. They may fall away 30 completely clear of the screen; or if they are carried again into contact with it they 35 are at once detached again and thrown farther toward the bottom of the screen. As the shocks follow each other in rapid succession the screen is thus kept almost constantly free from particles resting against 40 its surface and its capacity is maintained at a very high value. For preventing pulp from entering between the screen frame and the housing, the joint may be covered with a pliable strip of fabric or rubber *p*; or clear 45 water may be injected into the joint in the well known manner. *q* is a trough at about the level of the top of the screen and *r* an outlet forming therewith a spillway or bypass for passing surplus pulp from compartment *c* independently of the screen. In 50 the operation of this device the pulp in passing through passage *f* is subjected to hydraulic classification according to well known principles, whereby a greater or less 55 amount of the heavier and (or) larger (*i.e.* the less buoyant) particles tends to settle and pass off through the slot *g*. Thus when treating crushed ore comprising relatively light material such as quartz and heavier 60 material such as pyrite, the particles of pyrite, although usually of relatively small volume, tend to settle with the larger quartz particles. The smaller and (or) lighter (*i.e.* the more buoyant) particles, together with 65 such of the larger particles as failed to set-

tle, continue with the stream into compartment *c* of the classifier. The stream enters said compartment with considerable velocity, which however is rapidly diminished as the material moves up the compartment *c* owing to the flaring of said compartment and to the outflow of liquid and finer material through the screen. Consequently the less buoyant material still carried by the stream is to a large extent caused 70 to settle without coming into contact with the screen at all. Finally the screen stops all the remaining large particles, while permitting the smaller particles to pass through it with the stream. The large particles settled hydraulically in chamber *c* fall down principally at the back of said compartment near to the partition *d* and at the front near to the screen, at both of which places the velocity of the current 75 is reduced owing to skin friction. Those which settle at the back of the compartment fall from the lower end of the backwardly sloping part of partition *d* through the stream passing up from passage *f* and are 80 thereby subjected to further washing or classification. The whole of the oversize particles ultimately pass down passage *f* near to the walls thereof—where the velocity of the current is reduced owing to its 85 friction against the walls,—and thus they reach the slot *g*. In the event of the screen becoming choked by large floating material such as bits of wood, cinders and the like, the pulp will pass off from compartment *c* by way of trough *q* and outlet *r* carrying the floating particles with it and so 90 causing the screen to be cleared. Such arrangement moreover obviates difficulty due to a casual excess of flow beyond the capacity of the screen, without deranging the character of the products, since the surplus pulp will generally be properly graded owing to its diminished velocity due to the 95 widening of compartment *c* at the top and to the escape of most of the water through the screen. The surplus pulp passed off through *r* may be returned to that flowing off through the screen. The apparatus may 100 if desired be so operated as to cause a constant outflow from the spillway. 105
The device described in so far as it consists of the passage *f*, slot *g*, receiver *h* and water inlet *k* does not differ essentially from known upward current classifiers. An apparatus comprising these parts and affording free overflow from the top of the rising part of passage *f* would classify material to 110 the same extent as the average hydraulic classifier in commercial use. It would also exhibit the defect of the usual classifiers, that is to say that if it were so worked that substantially none of the material which it 115 is desired to carry off with the overflow be allowed to settle through slot *g*, then an im- 120
125
130

moderate quantity of material which it is desired so to settle would inevitably be passed off also with the overflow. In order to combine the vertical screen with such a classifier, the chamber *c* is provided to accommodate the pulp after it has issued from the classifier proper and while it is passing to the screen; said chamber being relatively tall as compared with the classifier proper owing to the smaller flow possible per unit of screen area as compared with the flow per unit of free overflow area. Said chamber however besides serving this purpose, also enables further hydraulic classification of the stream to be effected as already described, thus aiding in keeping the screen free. It is to be noted that the addition of chamber *c* is not merely the equivalent of making the hydraulic classifier deeper or in other words converting it into a spitzluttet, since if the lower part of the classifier were already designed for proper hydraulic separation, raising its outlet by means of chamber *c* would simply cause it to choke up. Such choking in the present case is obviated by the flow of pulp through the screen from the bottom to the top of chamber *c*.

Fig. II shows an ordinary cone classifier fitted with a cylindrical reciprocating screen *l* for the overflow. The equivalent of the chamber *c* above the classifier proper as shown in Fig. I, is here constituted by the space inclosed by the screen. A trough *q* forming a spillway may conveniently be mounted on the inlet pipe *e*. Similarly a spitzkasten may have its discharge side fitted with a reciprocating screen.

It will be manifest that where a classifier is adapted to give more than two products, each of the products beyond the largest may be passed through a screen of appropriate mesh and arranged in accordance with this invention.

What I claim and desire to secure by Letters Patent is:—

1. The combination of a hydraulic classifier having an underflow outlet for less buoyant material separately from the more buoyant material and constructed for continuous separation of less buoyant material from more buoyant material, a reciprocating

screen forming with parts of said classifier a compartment adapted to contain pulp, said screen providing the outlet for more 55 buoyant material and being so positioned that oversize material may fall directly from it by gravity.

2. The combination of a hydraulic classifier having an underflow outlet for less 60 buoyant material separately from the more buoyant material and constructed for continuous separation of less buoyant material from more buoyant material, and a substantially vertical reciprocating screen forming with parts of said classifier a compartment adapted to contain pulp and providing 65 the outlet for more buoyant material.

3. The combination of a hydraulic classifier having a restricted passage comprising 70 a rising portion and an underflow outlet at the lower end of said rising portion, and a reciprocating screen positioned to receive pulp from said rising portion and to permit oversize rejected by it to fall directly by 75 gravity to the lower side of said rising portion of the passage and thence to the outlet.

4. The combination of a hydraulic classifier having an underflow outlet for less 80 buoyant material separately from the more buoyant material and constructed for continuous separation of less buoyant material from more buoyant material, a chamber forming an extension thereof into which the more buoyant material passes, and a 85 vertical reciprocating screen bounding said chamber.

5. A structure having an upwardly flaring compartment, a substantially vertical screen bounding said compartment, means 90 for reciprocating the screen, said structure also having a restricted pulp inlet passage opening into the compartment obliquely at the base of the screen and a slot in the lower wall of said passage, and receiving means 95 into which said slot opens.

In testimony whereof I have signed my name to this specification in the presence of two subscribing witnesses.

GEORGE HARDY STANLEY.
